SUBMERSIBLE TANK FOR SUPPORTING
OFFSHORE STRUCTURES

Howard C. Rutledge and Richard M. Adler,

Shipbuilding Corporation, a corporation of
Delaware

Application October 3, 1949, Serial No. 119,324

6 Claims. (Cl. 61—46)

1

Our present invention relates to a submersible tank or vessel for supporting off-shore structures such for instance as apparatus for drilling and pumping oil wells, and has for an object the provision of a tank or vessel of the character designated which may be constructed and outfitted in a suitable way or in a dock or the like adjacent the shore and then floated to the well location and sunk to the floor or bottom of the body of water, thereby firmly supporting the well rigging above water.

Another object is to provide a supporting tank of the character designated which shall be stable while being transported and while being submerged, the tank being so constructed, ballasted and compartmented that the free liquid surface therein during the submerging operation is reduced to a minimum, whereby during the critical stage in the submerging operation the metacenter remains sufficiently above the center of gravity to make the vessel stable.

A more specific object is to provide a submersible tank for supporting off-shore structures which is divided vertically into at least two compartments, the wall or deck defining the two compartments being so located that when the lower compartment is completely flooded the upper deck of the tank is full above water, together with means dividing the upper compartment into sub-compartments whereby the final submergence of the tank is caused by selectively flooding the sub-compartments.

Further objects are to provide a platform for supporting the well drilling equipment, living quarters and the like, in turn supported from the tank by columns and to make the unsupported lengths of such columns as short as possible by means of readily installed cross bracing; to provide a columnar support which shall have minimum resistance to wave action; to provide a support which can be submerged or raised for removal to a different location without loss of materials such as is usually incident to the erection and removal of piling type supporting structures; and in general to provide means of the character designated which shall be economical of construction, require a minimum number of auxiliary service vessels such as tugs, barges and the like and which includes means for storing oil pumped from the well.

Apparatus illustrating the features of our invention is shown in the accompanying drawings forming a part of this application in which:

Fig. 1 is a diagrammatic, isometric view of a submersible tank showing the platform in place

2

thereon together with a diagrammatic showing of a portion of the drilling derrick, living quarters and the like, much of the equipment being eliminated for the sake of clarity.

5 Fig. 2 is a sectional view taken along line II—II of Fig. 1 and partly broken away;

Fig. 3 is a fragmental sectional view taken generally along line III—III of Fig. 2;

Fig. 4 is a sectional view taken generally along line IV—IV of Fig. 3;

Fig. 5 is a wholly diagrammatic view illustrating the pumps, conduits and valves for flooding and pumping out the various compartments of the tank; and,

15 Figs. 6 and 7 are diagrammatic views illustrating the forces tending to hold the entire structure in upright position while floating and during the submerging operation.

Referring now to the drawings for a better 20 understanding of our invention, and more particularly to Fig. 1, we show our improved form of supporting tank indicated generally by the numeral 10 and having secured to the upper deck 11 thereof a plurality of columns 12. Supported on the upper ends of the columns 12 is a deck or platform 13 on which in turn is mounted the well derrick 14, living quarter 16, cranes 17, and other machinery, not shown, incidental to the drilling of oil wells. For the sake of clarity substantially all of the internal strengthening members are omitted from the drawings, as well as crossbracing for the columns 12.

As best shown in Figs. 2, 3 and 4, the tank 10 is generally circular as viewed in plan. More particularly, the tank is shown in the form of a cylinder having an outer wall 18 and an inner cylindrical wall 19 concentric with the outer wall, both of which extend from top to bottom of the tank. The bottom of the tank is indicated at 21. It will be understood that the walls 18 and 19 are joined by welding or otherwise to provide water and oil tight joints.

Between the bottom 21 and deck 11 is an intermediate deck 23 which may consist of an annular plate and which is joined along its inner and outer edges 24 and 26 to the inner and outer sides respectively of the walls 18 and 19. This intermediate deck divides the tank into upper and lower compartments indicated generally by

50 the letters A and B respectively. A circular deck 27 made up of plates and which may be located at the same level as the deck 23, divides the central part of the tank into upper and lower compartments 28 and 29.

55 The upper compartment A is subdivided into

compartments 31 through 38 inclusive by means of a plurality of radially extending bulkheads 39 to 46 inclusive. The bulkheads 40, 42, 44 and 46 extend the entire height of the vessel, being joined at their upper and lower ends in water tight manner to the deck 11 and bottom 21. Thus, the compartment B is subdivided by the bulkheads 40, 42, 44 and 46 into sub-compartments 47 to 50 inclusive as is more particularly illustrated in Fig. 4.

As shown in Figs. 3 and 4, the entire bottom of the tank included within the compartments 47 to 50 inclusive, and 29, is covered with a layer 51 of reinforced concrete material or the like to serve as ballast in the manner later to be explained and to stiffen the bottom and distribute the vertical load of the superstructure equally over the bottom of the vessel. Beneath each of the columns 12 other than those connected to the deck over the inner and outer walls 19 and 18, we provide supplementary columns 30. The columns 30 are parallel with their associated columns 12 and rest on base plates 30a on top of the layer of concrete 51. By this means the load on the columns 12 is transmitted to the bottom 21 either through the walls 18 and 19 or through the supplementary columns 30.

The compartment 28 at the center of the vessel or tank may be utilized as a pump room. Likewise, it may be utilized as a general control room for the various valves which are used for submerging the vessel 10, pumping out the compartments, and pumping oil thereinto. In each of the compartments 47 through 50, and 29 we provide a sea valve 52 having a horizontally disposed control rod 53 and a vertically disposed control rod 54 having an operating wheel 56 thereon. The valve 52 for compartment 29 has a conduit 29a leading through the outer wall 18. Similarly, in each of the compartments 31 through 38 inclusive, immediately above the deck 23, we provide sea valves 57 having an operating rod 58 therefor with an operating wheel 59 disposed in the control compartment 28. By means of the sea valves 52 and 57 the several compartments may be selectively flooded in the manner later to be explained, thus to submerge the vessel 10. Access to the compartment 28 may be obtained by means of a tubular hatchway 61 having therein a ladder 62.

Referring particularly to Figs. 2 and 5, within the compartment 28 we provide a pump 66 which may be operated by any suitable motive power, for instance an electric motor 67. The discharge side of the pump 66 is connected by a line 68 which leads to the outside of the tank. The intake side of the pump is connected by a line 69 to a manifold conduit 71. The manifold is in turn connected by a conduit 72 to each of the compartments 31 through 38, inclusive, 47 through 50 inclusive, and 29. Each of the conduits 72 has therein a valve 73, also located in the pump compartment 28. By this means it will be apparent that the several compartments may be pumped out selectively thus to refloat the vessel 10.

Referring now particularly to Fig. 5, we show means for also pumping oil into the compartments selectively to store the same as it is produced from the well. As illustrated, we provide a second pump 74 having its intake side connected to a conduit 76 under control of a valve 77. The conduit 78 leading to the intake side of the pump is provided with a valve 79, and the

discharge conduit 81 leading from the pump 74 is provided with a valve 82. A by-pass line 83 having therein a valve 84 connects the conduits 78 and 81. Likewise, there is provided in the line 68 associated with the pump 66 a valve 85, and a valve 87 is interposed in the line 69 leading from the manifold pipe 71 to the intake connection of pump 66. By the arrangement shown it will be seen that the several conduits 72 leading to the various compartments may be utilized either to pump water therefrom or to pump oil thereinto. When pumping oil into the compartments the sea valves may be opened to permit the water therein to be displaced by the oil. While not shown in the drawings, the compartments may be provided with vent connections and control valves therefor. Thus, by closing valve 81, valve 82, and valve 79 oil from a suitable source delivered to the pump 74 through the line 76 passes through the cross conduit 83 and into the manifold pipe 71. By suitable manipulation of the valves 73, 52 and 57 it will be apparent that a selected compartment may be filled with oil and the water therein displaced.

23 The actual drilling operation takes place through a plurality of tubes 88 passing vertically through the decks 11 and 27 and bottom 21 of the tank and which may extend up through the deck 13 under the well derrick 14. While we show tubes 88 for this purpose it will be apparent that by suitable means a portion of the central opening may be made water tight from the remainder thereof by means of plates, thus to leave an arcuate opening for passing the drilling tools.

33 From the foregoing the method of constructing and using our improved apparatus may now be explained and understood. As is understood in the art to which this invention relates the principal criterion of stability of floating and submerged vessels is the vertical distance between the metacenter and the center of gravity. By definition the metacenter is the point of intersection M of the vertical through the center of buoyancy B of a body floating or suspended in a liquid with the vertical through the new center of buoyancy B' when the body is angularly displaced however little. See Figs. 6 and 7. When the point M is above the center of gravity G of the body the position of the body is stable; when below it, unstable; when coincident with it, neutral. When the upper deck or surface of a vessel passes beneath the surface of a liquid, or in other words when the vessel is suspended in the liquid, the metacenter is, except as affected by factors such as free liquid surface, at the center of buoyancy B. When there is free liquid surface within the vessel the metacenter is lowered by a determinable amount. Thus, with a free liquid surface in a vessel being submerged the point M moves downwardly, resulting in a loss of metacentric height GM, Figs. 6 and 7, and consequently lowering the degree of stability of the vessel.

60 Should the intermediate decks 23 and 27 of our improved vessel be located so high that at the time of submergence there exists a large amount of free liquid surface within the lower compartments the stability of the vessel would be of a low order. To overcome this we locate the intermediate decks 23 and 27 at a point vertically between the upper deck 11 and bottom 21 so that when the lower compartments are all completely flooded the vessel remains with its upper deck just above water. Furthermore, we propose to keep the center of gravity G substantially below the metacenter in floating and sub-

65 70 75

merged conditions by the ballasting material 51. We have found that the metacentric height is maintained positive and of a sufficient magnitude to assure stability by locating the deck at the height just explained and by subdividing the upper and lower compartments. This vertical and horizontal subdivision of the vessel in addition to reducing free liquid surface loss in metacentric height, further increases metacentric height by permitting the ballast water to be placed as low as possible and thus contributes to the lowering of the center of gravity G. Without the intermediate decks 23 and 27, to decrease the free liquid surface loss in metacentric height, the compartments necessary to lower the vessel to the degree accomplished by flooding all the lower sub-compartments would have to extend up to the deck 11, thus raising the center of gravity G. During the time until the deck 11 of the tank remains just above the water line W the free surface loss in metacentric height is kept low by subdivision of the lower compartment B. As is understood, the loss in metacentric height when free liquid surface is present is directly proportional to the sum of the moments of inertia of the individual surfaces in the compartments. With the tank remaining just above water, the flooding to completely submerge the same is restricted to the required number of the small compartments above the intermediate deck 23. The net result of the construction shown including the ballasting material 51 is the provision of a vessel of the character designated which is stable in floating condition and which also is stable at the critical point during the submergence thereof, namely, when the upper deck 11 passes beneath the water line. Thus, by locating the intermediate deck 23 at a point whereby when the lower compartments are flooded without causing complete submergence of the vessel, dividing the upper compartment into sub-compartments, and selectively flooding the latter to complete submergence, we have provided a vessel which is stable in all conditions. The dead weight and moments of the platform 13, the derrick and other structures and equipment on the platform can be effectively counterbalanced by the weight of the vessel itself with the aid of the ballasting material 51 so that the center of gravity of the whole system, including water ballast, will remain always below the metacenter.

While we have shown means for selectively flooding all of the upper compartments 31 through 38 inclusive it may well be found that some of these compartments will not be needed for this purpose and may be utilized for the storage of fuel or wet or dry supplies for use in the drilling operation. As will be apparent, whether or not these are available for purposes other than flooding can be readily determined by calculations and considerations which take into account the design of the vessel and the super-structure therefor.

From the foregoing it will be apparent that we have devised an improved tank or vessel for supporting off-shore structures. While we have shown our invention as especially adapted for the support of oil well drilling equipment it will be apparent that the same may be used for other purposes if desired. It will also be apparent that by suitable manipulation of the valves and pumps shown diagrammatically in the drawing the vessel may be refloated by pumping out the compartments. If desired the water in the compartments may be displaced by pumping thereinto

oil from the well, thus simultaneously keeping the vessel submerged and affording storage space for the oil. Our invention is particularly characterized by the fact that it can be moved from place to place without loss of material such as piling or the like. Due to the fact that it is stable both during towing and during the submerging operation our improved apparatus is capable of use in water of upwards of 100 feet in depth. Also, the cross bracing of the columns 12, not shown in the drawings may be installed and repaired with ease since when the vessel is afloat these columns are out of the water. Thus the unsupported length of such columns 12 may be reduced to the optimum.

The circular shape of the vessel has, among others, the structural advantages of strength, simplicity of construction and high strength-weight ratio. Hydrodynamically this shape has the advantage of offering minimum resistance to the varying forces due to waves, currents and winds, regardless of direction and magnitude.

While we have shown our invention in but one form, it will be obvious to those skilled in the art that it is not so limited, but is susceptible of various other changes and modifications, without departing from the spirit thereof, and we desire therefore, that only such limitations shall be placed thereupon as are specifically set forth in the appended claims.

What we claim is:

1. In means for supporting off-shore structures, a tank, a horizontal deck in the tank dividing the same into upper and lower water tight compartments, vertical bulkheads dividing the upper compartment into a plurality of water tight sub-compartments, said upper compartments having sufficient buoyancy when substantially empty to float the tank when the lower compartment is substantially completely flooded, and means to flood the lower compartment and a sufficient number of the upper compartments to submerge the tank.

2. In means for supporting off-shore structures, a tank having an upper deck on which the structure to be supported is mounted in spaced relation thereto, an intermediate horizontal deck defining with the upper deck and bottom of the tank a pair of water tight compartments, the relative volume of said compartments being such that when the lower compartment only is flooded the upper deck remains above water, water tight bulkheads dividing the compartments vertically into upper and lower sub-compartments, means to flood all of the lower sub-compartments thereby reducing to zero the liquid free surface therein, and means to selectively flood a sufficient number of the upper compartments to cause the tank to submerge with its upper deck below the water line.

3. In means for increasing the stability of a submersible vessel having sides and upper and lower decks, an intermediate deck dividing the vessel into upper and lower water tight compartments, said deck being located vertically at a point whereby when the lower compartment is flooded the vessel remains afloat, a quantity of ballasting material distributed substantially equally over the bottom of the vessel, vertically disposed bulkheads dividing the upper and lower compartments into sub-compartments, means to flood the lower sub-compartments, and means to flood at least one of the upper compartments to submerge the vessel.

4. In a submersible vessel for supporting off-

shore structures; a cylindrical water tight tank having sides and upper and lower decks, columns secured to the upper deck and disposed to support the structure above water, an intermediate deck parallel with the upper and lower decks dividing the interior of the body into upper and lower compartments, said intermediate deck being located at the point whereby when the lower compartment is flooded the upper deck remains above water, radially disposed bulkheads dividing the upper and lower compartments into sub-compartments of substantially equal size, other radially disposed bulkheads above the intermediate deck dividing the upper sub-compartments into smaller substantially water tight compartments, means to flood all of the lower compartments, and means to admit water selectively to a sufficient number of the upper smaller compartments after all of the lower compartments are fully flooded to submerge the tank.

5. In apparatus for drilling off-shore oil wells, a cylindrical water tight vessel having a top and bottom and being of sufficient displacement to support a well drilling rig disposed to be floated into position and then sunk onto the bottom of a body of water, a horizontal deck dividing the vessel into upper and lower water tight compartments and located at a height whereby when the lower compartment is flooded the vessel remains afloat, vertical radially extending bulk-

heads extending between the top and bottom of the vessel sub-dividing the upper and lower compartments into sub-compartments of substantially equal size, other vertical radially disposed bulkheads dividing the upper sub-compartments into smaller compartments, a layer of ballast material distributed evenly over the bottom of the vessel, and means to selectively flood the lower sub-compartments and upper smaller compartments.

10 6. A submersible vessel as defined in claim 2 in which the bottom of the tank has distributed substantially evenly thereover ballasting material sufficient to counterbalance the weight of
15 the structure supported in spaced relation to the upper deck of the tank.
